RAILWAY TRAFFIC CONTROLLING APPARATUS

Filed Feb. 5, 1924

Fig. 1.

Fig. 2.

UNITED STATES PATENT OFFICE.

CHARLES H. LAY, OF LOS ANGELES, CALIFORNIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed February 5, 1924. Serial No. 690,735.

My invention relates to railway traffic controlling apparatus, and particularly to apparatus of the type comprising trackway signals controlled in accordance with traffic conditions.

I will describe one form of trackway apparatus embodying my invention, and will then point out the novel features thereof in claims.

10 In the accompanying drawing, Fig. 1 is a diagrammatic view showing one arrangement of signals to which my invention may be applied. Fig. 2 is a view showing one form of apparatus embodying my invention applied to the control of signal S⁵ in Fig. 1.

Similar reference characters refer to similar parts in both views.

Referring first to Fig. 1, the reference characters *a* and *b* designate the track rails 20 of a portion of railway track over which traffic moves in both directions. This portion of track is divided, by passing sidings *M*, *N* and *O*, into two stretches *A*—*D* and *E*—*H*. Stretch *A*—*D* is further divided 25 by means of insulated joints 17, into a plurality of successive track sections *A*—*B*, *B*—*C*, *C*—*D*. In similar manner stretch *E*—*H* is divided into track sections *E*—*F*, *F*—*G*, *G*—*H*.

30 Traffic through the stretch *E*—*H* from east to west is governed by signals S¹, S³ and S⁵, while traffic through this stretch in the opposite direction is governed by signals S⁸, S⁶ and S⁴. Stretch *A*—*D* is similarly provided with signals S⁹, S¹¹, S¹³, S¹⁶, S¹⁴ and S¹². The passing siding *N* is protected 35 by signals S¹⁰ and S⁷. As here shown a pair of opposing signals is located adjacent each end of each section, although I do not desire 40 to be limited to this particular location and distribution of the signals.

The signals for stretch *A*—*D* are so controlled that when a train moving toward the east enters this stretch signals S⁹, S¹¹ and S¹³ 45 are placed at stop. Signal S⁹ remains at stop till the train has moved out of the stretch thus prohibiting a westbound train from entering the stretch. As the eastbound train enters the stretch, it also causes signal S¹⁶ to indicate stop, and as it passes signals S¹⁴ and S¹² these signals also display stop indications. When the train clears section 50 *A*—*B*, signal S¹⁶ changes to the caution indi-

cation, and when the entire train passes out of section *B*—*C*, this signal returns to the proceed indication. Signal S¹⁴ changes to the caution position when the train moves out of section *B*—*C* and to proceed when the train moves out of section *C*—*D*. Two or more trains may therefore follow each other 60 through the stretch under the same signal protection as is customarily provided for double track roads. Similarly when a westbound train enters stretch *A*—*D*, signals S¹, S³, S⁵ and S¹⁶ are placed at stop and signal S⁹ subsequently changes successively to caution and proceed. Signal S¹¹ changes to stop when passed by the train and subsequently changes to caution and proceed as the train clears the next section in advance 70 and the second section in advance, respectively.

The signals for stretch *E*—*H* are controlled in the same manner as the signals for stretch *A*—*D*.
75

Whenever signal S⁹ indicates stop, signal S⁷ of course indicates caution, and whenever signal S⁷ indicates stop signal S⁵ indicates caution. Moreover, when an eastbound train occupies stretch *A*—*D* signal S⁵ as well 80 as signal S⁷ indicates caution, but when a westbound train has passed signal S⁹, thus allowing signal S⁷ to indicate caution, signal S⁵ indicates proceed.

Ordinarily, when an eastbound train 85 passes signal S¹³ this signal remains at stop till the train passes out of section *B*—*C*, and signal S¹¹ remains at stop till the train passes out of section *C*—*D*. Similarly, when an eastbound train passes signal S⁵, this signal 90 ordinarily remains at stop till the train passes out of section *F*—*G*.

Signaling systems operating in this manner are well known in the art as absolute permissive block signaling systems, and various known means may be provided to accomplish the desired operation.
95

It is desirable, however, when an eastbound train moves out of section *E*—*F*, to have signal S⁵ display a proceed indication 100 provided sections *D*—*E* and *E*—*F* are unoccupied. The reason for this is to allow back-up moves which may be necessary or desirable in manipulating trains in the neighborhood of a passing siding.
105

The object of the present invention there-

fore is the provision of novel and simple means for permitting this operation of signal S^5 .

Referring now to Fig. 2, the main track of siding N is provided with a track battery 18 and a track relay R^7 . Section E—F is divided into two sub-sections E—J and J—F. Sub-section E—J is provided with a battery 18 and a track relay R^8 , and sub-section J—F 10 is provided with a similar battery 18 and track relay R^9 .

Located adjacent track relay R^8 is a polarized relay K^8 . This relay K^8 is provided with a circuit which passes from battery 60, 15 through the upper arm of pole-changer P^6 , wires 61 and 62, contact 63 of the relay K^6 , wire 64, contact 65 of track relay R^9 , wire 66, contact 67 of track relay R^8 , wire 68, winding of relay K^8 , wire 69 and lower arm 20 of pole-changer P^6 to battery 60. Pole-changer P^6 is operated by a signal S^6 in such manner that the pole-changer is in normal position when the signal indicates proceed or caution, but in reverse position when 25 the signal indicates stop. Located adjacent relay K^6 is an auxiliary relay X^6 which is controlled in such manner that it is normally de-energized, but becomes energized when an eastbound train passes signal S^6 . 30 When once energized, relay X^6 remains energized until the eastbound train passes out of section F—G. The circuit for relay K^8 is provided with a branch around contact 63 of relay K^6 , which branch passes from wire 35 61, through wire 70, contact 71 of relay X^6 , and wire 72 to wire 64. Relay K^6 is provided with a circuit similar to the circuit for relay K^8 , that is, relay K^6 is controlled by the track relays for section F—G and by 40 relays located at signal S^4 and similar to relays K^6 and X^6 at signal S^6 . Similarly the relay of signal S^4 , corresponding to relay K^6 , is controlled by the track relays for section G—H. It will be seen, therefore, that relay 45 K^8 is energized in the normal direction when the track is unoccupied, is de-energized when a westbound train is between points E and H, and also when an eastbound train is in section E—F, and is energized in the reverse 50 direction when an eastbound train is in section F—G. The control of relay K^8 is in accordance with standard practice in absolute 55 permissible block signaling, and such control is illustrated, for example, in United States Letters Patent No. 1,400,964, granted to R. A. McCann on Dec. 20, 1921, in which patent relay R^{12} corresponds to relay K^8 of the present disclosure.

There is also provided a pole changing relay L which is controlled by means forming no part of the present invention and omitted from the drawing, so that under normal conditions, this relay is energized. Relay L is de-energized, however, from the time an 60 eastbound train enters stretch A—D, until 65

such train passes point E, and is also de-energized when a westbound train passes signal S^7 and until such westbound train reaches a point in section C—D. One arrangement of apparatus for controlling the pole changer relay L in this manner is shown in the said United States Patent No. 1,400,964, issued Dec. 20, 1921, to R. A. McCann. The pole changer relay here referred to is designated M in the specification and drawings of that patent.

I also provide a second polarized relay K^5 for controlling signal S^5 as follows:

Signal S^5 is provided with a proceed operating circuit which may be traced from a suitable source of energy such as a battery 20, through wire 40, front contact 41 of relay K^5 , wires 42 and 45, normal contact 46 of relay K^5 , wire 47, operating mechanism of signal S^5 , and wire 44 back to battery 20. 80 This circuit is closed only when relay K^5 is energized in the normal direction under which conditions signal S^5 displays a proceed indication. When relay K^5 is energized in the reverse direction the circuit for signal S^5 passes from battery 20, through wire 40, front contact 41 of relay K^5 , wires 42 and 43, operating mechanism of signal S^5 , and wire 44 back to battery 20. 85 When this circuit is closed signal S^5 indicates caution. 90 When relay K^5 is de-energized, both circuits for signal S^5 are opened and the signal displays a stop indication.

Relay K^5 is supplied with energy from a suitable source, such as a battery 19 over a circuit which passes through wire 21, front contact 22 of relay L , wires 23 and 24, normal contact 25 of relay K^8 , wire 26, front contact 27 of relay K^8 , wire 28, front contact 29 of track relay R^8 , wire 30, front contact 31 of track relay R^5 , wire 32, winding of relay K^5 , wire 33, front contact 34 of relay L , wire 35, and back to battery 19. 100 When this circuit is closed the current supplied to relay K^5 is of such polarity that the relay is energized in the normal direction.

When relay L is de-energized and relay K^8 is energized, as when a westbound train occupies section D—E, the circuit for relay K^5 may be traced from battery 19, through wires 21 and 36, back contact 34 of relay L , wire 33, winding of relay K^5 , wire 32, front contact 31 of relay R^5 , wire 30, front contact 29 of relay R^8 , wire 28, front contact 27 of relay K^8 , wire 26, normal contact 25 of relay K^8 , wires 24 and 23, back contact 22 of relay L , and wire 35 back to battery 19. 110 When this circuit is closed relay K^5 is supplied with current of such polarity that this relay is energized in the reverse direction.

When a train moving from east to west is between F and H, relay K^8 is de-energized, and a branch is closed for either of the circuits just traced which branch connects wire 23 directly with wire 28 by means of back 115 120 125 130

contact 27 of relay K⁵. Relay K⁵ is therefore energized in one direction or the other according as relay L is energized or de-energized, provided relay K⁵ is energized in the normal direction, or de-energized, and provided relays R⁸ and R⁵ are energized.

It will be plain that the presence of a train in either sub-section E—J or J—F, will de-energize the corresponding track relay and hence will cause signal S⁵ to display a stop indication by the de-energization of relay K⁵.

A train moving from west to east, however, after moving out of sub-section J—F, will allow the energization of relay R⁵, and relay K⁵ will then be energized as long as such train is in section F—G. Assuming section D—E and sub-section E—J to be unoccupied, relays R⁷ and R⁸ will also be energized. If relay L be energized current will flow from battery 19, through wire 21, front contact 22 of relay L, wires 23 and 38, front contact 39 of relay R⁷, wire 50, reverse contact 25 of relay K⁵, wire 26, front contact 27 of relay K⁵, wire 28, front contact 29 of relay R⁸, wire 30, front contact 31 of relay R⁵, wire 32, winding of relay K⁵, wire 33, front contact 34 of relay L, and wire 35 back to battery 19. When this circuit is closed relay K⁵ is of course energized in the normal direction and signal S⁵ displays a proceed indication to permit the train in section F—G to return into section E—F. It is thus plain that the only time when the proceed indication of signal S⁵ is controlled by traffic conditions in section D—E is when relay K⁵ is energized in the reverse direction, which can occur only when an eastbound train occupies section F—G.

Although I have herein shown and described only one form and arrangement of railway traffic controlling apparatus embodying my invention, it is understood that

various changes and modifications may be made therein within the scope of the appended claims without departing from the spirit and scope of my invention.

Having thus described my invention, what I claim is:

1. In combination, a stretch of track divided into a right-hand section and a left-hand section, a signal for governing traffic from right to left through said right-hand section, a relay arranged to be de-energized when a train moving from right to left approaches said left-hand section but to be energized when a train moving from left to right passes said signal, a second relay, means for energizing said second relay when said first relay is de-energized and said right-hand section is unoccupied, means for at times energizing said second relay when said first relay is energized and said right-hand and said left-hand sections are both unoccupied, and means controlled by said second relay for operating the signal.

2. In combination, a stretch of track divided into a right-hand section and a left-hand section, a signal for governing traffic from right to left through said right-hand section, a relay arranged to be de-energized when a train moving from right to left approaches said left-hand section or a train moving from left to right occupies said right-hand section but arranged to be energized in the normal direction at times when a train moving from left to right occupies said left-hand section and to be energized in the reverse direction when a train moving from left to right passes said signal, and means for causing the signal to indicate proceed when said relay is energized in the reverse direction and said left-hand section is unoccupied.

In testimony whereof I affix my signature.

CHARLES H. LAY.
